US00D574323S

(12) **United States Design Patent**
Waaler

(10) **Patent No.:** **US D574,323 S**
(45) **Date of Patent:** **** Aug. 5, 2008**

(54) **GENERATOR**(75) Inventor: **Luke Waaler**, Longmont, CO (US)(73) Assignee: **Tyco Healthcare Group LP**, North Haven, CT (US)

Primary Examiner—Prabhakar Deshmukh*Assistant Examiner*—Derrick Holland(57) **CLAIM**

The ornamental design for a generator, as shown and described.

DESCRIPTION

FIG. 1 is a front perspective view of a generator showing my new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevational view thereof; and,

FIG. 8 is a left side elevational view thereof.
